(57) **CLAIM**

The ornamental design for an indoor wall for the built-in home appliances, as shown and described.

DESCRIPTION

FIG. 1 is a top perspective view of the indoor wall for the built-in home appliances showing our new design;

FIG. 2 is a bottom perspective view thereof;

FIG. 3 is a front view thereof;

FIG. 4 is a rear view thereof;

FIG. 5 is a left side view thereof where the right side view is a mirror image;

FIG. 6 is a top plan view thereof where the bottom plan view is a mirror image; and,

FIG. 7 is a reference view showing the state of use that the clothes management apparatus has been separated from the frame by using the handles at both sides of the inside of this design.

The broken lines depict portions of the indoor wall for the built-in home appliances that form no part of the claimed design.
